UNITED STATES PATENT OFFICE.

HERBERT C. COOK, OF SPRINGFIELD, MASSACHUSETTS.

COMBINATION DARNING-BALL AND HANDY IMPLEMENT.

1,048,296.

Specification of Letters Patent.

Patented Dec. 24, 1912.

Application filed May 11, 1912. Serial No. 696,610.

To all whom it may concern:

Be it known that I, HERBERT C. COOK, a citizen of the United States of America, and resident of Springfield, in the county of 5 Hampden and State of Massachusetts, have invented certain new and useful Improvements in Combination Darning-Balls and Handy Implements, of which the following is a full, clear, and exact description.

10 The object of this invention is to provide a device which is available for utilization for several purposes,—that is it is primarily to be employed as a darning ball; furthermore, as a last or form for the mending of 15 the thumb and the large and small fingers of gloves, and also as a device by means of which the tubular rods of various sizes may be "threaded" or engaged through the 20 hems of sash, lace or other curtains or portières.

The invention is described in conjunction with the accompanying drawings and is set forth in the claims.

In the drawings:—Figure 1 is a perspective view and Fig. 2 is a longitudinal sectional view of the complete device with the parts thereof all in engagement with each other. Fig. 3 is a side view showing the utility of the darning ball or last when it is 30 desired that a piece of fabric of character other than that of a stocking is to be mended while drawn to a taut condition over the darning ball. Figs. 4 and 5 illustrate uses of the handle portions of the device for 35 threading tubular curtain rods through different sized hems of sash curtains.

In the drawings, A represents the darning ball of ovoidal shape and made with a flattened face b at one side thereof; and the 40 darning ball has a rearwardly open socket d in its rear end.

B represents, generally, a handle by which the darning ball is carried, the same comprising a forward section f, an intermediate 45 section g, and a rear section h, each being of a greater diametrical size than the one next forward thereof. The forward and intermediate sections have their forward ends rounded as shown, and they are formed with 50 attenuated axial stems f² and g² at their rear ends and the stem g² of the intermediate section is provided with a rearwardly projecting pin g³. The intermediate and rear sections have sockets g⁴ and h⁴ in their forward ends 55 in which said stems are detachably engaged or bound with a crowding fit; and the for-

ward section f which is slightly tapered has a detachable crowding fit in the socket d in the ball. The stems f² and g² of the section f and g are formed for the greater portion 60 of their length with a gradual taper, but the angle of the tapering at the forward portion of each of such stems is of increased abruptness, as indicated at f⁵ and g⁵; and the socket mouths of the handle section into 65 which the said tapered stems are received have binding and retaining engagements with the tapered portions f⁵ and g⁵ of the stems, which are of the greater abruptness. This 70 last described special formation is one especially advantageous for employment in the device which is usually to be made of wood, as the interengaged part will always derive a seating and detachable confinement irrespective of changes resulting from swelling or shrinkage of the wood.

The darning ball comprising the sectionally formed handle will be employed in the ordinary manner when used in stockings. In some cases where a piece of fabric is to 80 be darned or mended the rear handle section may be removed, a portion of the fabric engaged with the pin or spur g³ and being held thereby may be drawn by the hand and maintained in a taut or more or less 85 stretched condition across the flattened face or the rounded face of the ball as desired while the darning is being performed. For employment as a last or form the rear handle section h, the rear end of which is 90 rounded, may be inserted in the large fingers of gloves, but for small glove fingers the forward section f, disconnected from the darning ball may be employed.

In Fig. 4 the tapered stem of the smaller 95 and forward handle section f is represented as engaged in the end of a tubular rod of comparatively small size preparatory to threading it through the hem j of a sash curtain; and in Fig. 5 the larger, intermediate section is similarly employed in conjunction with the tubular curtain rod i² of larger size.

I claim:—

1. The combination with a darning ball 105 having a socket in its rear end, of a handle comprising a forward, an intermediate, and a rear section, the forward and intermediate sections having rounded forward ends, and also having attenuated axial stems at their 110 rear ends, the intermediate and rear sections having sockets in their forward ends in

- which said stems are detachably engaged, and the forward section having a detachable engagement in the socket in the darning ball.
- 5 2. The combination with a darning ball having a socket in its rear end, of a handle comprising a plurality of sections the forward one of which has a detachable engagement in the socket of the darning ball and 10 one of the handle sections to the rear of another of such sections having a tapered stem and socket engagement, one of the stems being provided with a pin extending rearwardly from the end thereof, the socketed handle section to the rear thereof concealing and serving as a guard for such pin.
- 15 3. The combination with a darning ball having a socket in its rear end, of a handle comprising a forward, an intermediate, and
- a rear section, and each of greater diametrical size than the one next forward thereof, the forward and intermediate sections having their forward ends rounded, and formed with attenuated axial stems at their rear ends, the stem of the intermediate section having a rearwardly projecting pin, the intermediate and rear sections having sockets in their forward ends in which said stems are detachably engaged, and the forward section having a detachable engagement in the socket in the darning ball.
